UNITED STATES PATENT OFFICE.

EDWARD SYDNEY LUARD, OF LONDON, ENGLAND.

STEAM-SUPERHEATER FOR LOCOMOTIVE, MARINE, AND OTHER BOILERS.

1,077,617.

Specification of Letters Patent.

Patented Nov. 4, 1913.

Application filed January 11, 1912. Serial No. 670,588.

To all whom it may concern:

Be it known that I, EDWARD SYDNEY LUARD, a subject of the King of Great Britain and Ireland, residing at London, in the 5 county of London, England, (whose post-office address is Spencer House, South Place, London, in the county of London, England,) have invented certain new and useful Improvements in Steam-Superheaters 10 for Locomotive, Marine, and other Boilers; and I do hereby declare the following to be a full, clear, and exact description of the invention, such as will enable others skilled in the art to which it appertains to make 15 and use the same.

This invention has for its object improvements in steam superheaters of the multibular type and of the kind wherein a series 20 of superheater tubes or pipes are arranged in the fire tubes or flues of a locomotive or other fire tube boiler so that the said pipes will be heated by the gases of combustion, the said superheater pipes being connected 25 to a header or steam collector divided into two compartments into one of which compartments the saturated steam from the boiler enters and thence flows, through the superheater pipes, into the other compartment of the heater.

In superheaters of the type above mentioned it has heretofore been usual to form the header comprising the aforesaid two longitudinal compartments or chambers (one for the saturated steam and the other 35 for the superheated steam) of a single casting without any removable cover. Such construction of header is not only difficult and expensive to manufacture, but also necessitates the employment of special jointing means for connecting the ends of the superheater or steam circulating pipes to the header such jointing means giving considerable trouble, through leakage, and necessitating a considerable amount of time, labor and expense for keeping the joints 45 properly steam tight for service conditions. Further such header being in one piece, and the steam chambers or compartments therein being thus permanently closed, it is impossible to inspect the interior of the casting 50 and to detect and repair flaws therein, with the result that a large number of these headers when put under test have had to be scraped and complete new headers made to 55 replace them.

The principal object of the present in-

vention is to provide an improved form or construction of header whereby the above mentioned objections or disadvantages are eliminated, and a more efficient superheater 60 is also obtained.

According to the present invention the header, which preferably consists of a steel casting, is formed with a series of chambers or compartments arranged side by side and access to all of which chambers can be readily obtained by removing a cover with which the header is provided. Further the steam inlet and outlet ends of each superheater element or pipe are inserted in or directly connected to the bottom of the header, which forms a tube plate, and secured in the 65 said tube plate in a proper steam tight manner by expanding the said pipe ends into the said tube plate or bottom of the header which is provided with a number of holes, corresponding to the number of pipe ends to be secured in the header. The above mentioned pipe ends may be expanded into the bottom of the header by means of a suitable tube expanding tool or mandrel which may be introduced through holes provided in the top of the header, suitable screwed 70 plugs being also provided for closing the said holes. Or the said pipe ends might be expanded into the header by inserting the tube expanding tool or mandrel through the front open ends or sides of the steam compartments in the header.

The ends of the superheater pipes, when 75 it is desired to remove one or more of the said pipes, can be conveniently and rapidly driven out of the bottom of the header by means of a suitable tool inserted through the open front, ends or sides of the aforesaid steam compartments or chambers, the above mentioned removable cover being for 80 this purpose removed from the header.

The header according to this invention is 85 further so constructed that the superheated steam compartments are connected together by short transverse pipes or tubes, which may also be expanded into the header, these 90 short pipes being so placed as to be acted upon by the heated gases coming from the smoke or fire tubes into the smoke box.

The header according to this invention 95 has been principally designed to be placed, preferably transversely, in the upper part of the smoke box of a locomotive or like 100 fire tube boiler, preferably above the center lines of the uppermost fire or smoke tubes

so that the saturated steam inlet ends and the superheated steam outlet ends of each superheating element or pipe are bent from the smoke or fire tubes, into which they extend, to the header. This particular location of the header is not however essential to the main features of the invention as the header might be otherwise located in the smoke box without detracting from the 10 advantages obtained by this invention.

Further features of the invention will appear from the following description with reference to the accompanying drawing, in which,—

15 Figure 1 is a front view, partly in section and partly in elevation, of a superheater according to this invention fitted to a locomotive boiler. Fig. 2 is a vertical transverse section, taken on the line A, B Fig. 1, of 20 a header according to this invention, this figure also showing some of the superheater pipes connected to the header and a portion of the smoke box of the boiler. Fig. 3 is a plan view, partly in section, of a header 25 according to this invention, and shows the way in which the saturated and superheated steam ends of the superheater pipes are arranged in connection with the steam compartments of the header.

30 Like reference numbers indicate corresponding parts in the several figures of the drawing.

1 represents a portion of the smoke box of a locomotive boiler and 2 a portion of the 35 smoke box tube plate, 3 being smoke or fire tubes of ordinary size.

4 are enlarged smoke or fire tubes which are, as usual, arranged in horizontal and vertical rows in the upper portion of the 40 boiler.

5 are the superheater elements or steam superheating pipes each of which, as usual, extends into a smoke tube 4 each of these pipes 5 preferably, as usual, comprising 45 four horizontally disposed lengths of pipe extending into each smoke tube 4 and provided with suitable return bends or connections at their ends. The ends of the superheater pipes 5 which project into the smoke 50 box are, in the example shown, bent upwardly to the header 6.

5^a and 5^b indicate, respectively, the saturated steam inlet end and the superheated steam outlet end of each superheater pipe 55 or element 5. As clearly shown in Fig. 2 the parts of the ends 5^a, 5^b of the superheater pipes 5 adjacent to the header 6 are bent so as to be at right angles or substantially right angles to the bottom of the

60 header, the bottom or tube plate 6^a of the header being provided with a number of holes through it corresponding to the number of pipe ends 5^a, 5^b which are inserted and expanded in the said holes by means of 65 a suitable tube expanding tool or mandrel,

the arrangement of these holes with the pipe ends therein being clearly shown in Fig. 3.

The header 6, which preferably consists of a steel casting, is formed as shown with saturated steam compartments or chambers 7, 7^a and 7^b and with superheated steam compartments or chambers 8, 8^a, 8^b and 8^c, these several compartments or chambers being arranged side by side and transversely of the header so that the saturated and superheated steam compartments alternate in the header. The two end or outer saturated steam compartments 7^a and 7^b of the header are, as clearly shown in Fig. 1, formed in the upper part of the header and at a higher level than the remaining steam compartments or chambers of the header, these compartments 7^a and 7^b being connected to the central saturated steam compartment 7 and also to each other by means of a passage or channel, or passages or channels, 9 formed in the upper part of the header and extending across the tops of the superheated steam compartments 8^a and 8^b.

The superheated steam compartments 8 and 8^a and the superheated steam compartments 8^b and 8^c are connected by short transverse pipes or tubes 10, 10^a whose ends are expanded (by a suitable tube expanding tool or mandrel which may be inserted through the open fronts of the said compartments) into the adjacent side walls of the said compartments.

In the top of the header 6 there are provided a number of holes which are opposite to or in vertical alignment with the hereinbefore mentioned holes in the bottom or tube plate 6^a of the header, so that the tube expanding mandrel can be introduced into the header through the said top holes. 11, 11^a are screwed plugs of suitable metal, which are provided for closing the said holes in the top of the header such holes being provided with corresponding screw threads. It will be seen that the plugs 11^a are duplex or compound plugs, that is to say, these plugs are provided with screw threads at each end the inner or lower threaded ends of these plugs closing holes in the top of the superheated steam compartments 8^a, 8^b through which the mandrel can be introduced so as to operate upon the superheater pipe ends in connection with the said superheated steam compartments 8^a, 8^b. The threaded parts of the plugs 11, 11^a which engage in the correspondingly threaded holes in the top of the header are preferably tapered the said holes being correspondingly tapered.

12 indicates an inwardly projecting flange or plate formed at the outer open end of each of the steam compartments or chambers of the header, and 13 are screwed studs fitted in the said flanges or plates.

14 is the removable cover of the header.

which when placed on the front of the header closes the open front ends of all the steam compartments or chambers in the header with the exception of the end superheated steam compartments 8, 8^c to which latter compartments are connected the usual main steam pipes to the cylinder valve chests of the engine.

15 are the flanges or connecting plates of the main steam pipes 16 and by which the said pipes are connected to the end superheated steam compartments 8, 8^c for instance by means of bolts 17.

13^a are nuts which, when tightened up on the outer ends of the screwed studs 13, secure the cover 14 on the header, the said cover being provided with holes corresponding in number and arrangement to the number of screwed studs 13 which when the cover is placed in position project through the holes in the cover. The faces of the above-mentioned inwardly projecting flanges or plates 12 on the front of the header and the inner face of the cover 14 are machined or faced true so that when the cover 14 is placed in position and secured on the header an effective steam tight joint is made.

On the rear or inner side of the header, *i. e.* the side adjacent to the tube plate 2, there is formed a central tubular part or boss 18 having a flange 18^a adapted to receive suitable bolts or the like for securing the header to the smoke box tube plate 2 with the bore or passage 18^b through the part 18 in alignment with the end of the saturated steam pipe 19 through which steam passes from the steam dome or source of supply to the superheater header 6.

11^b, Fig. 1, are screwed plugs, similar to 11, which may be inserted in correspondingly screwed holes in the end walls of the header and in alignment with the outer ends of the small cross tubes or pipes 10 (respectively 10^a), through which holes a tube expanding mandrel may be introduced for the purpose of expanding the outer ends of the said cross tubes in the header.

The openings at the front side of the header are all of large size, so that when the cover plates 14 and 15 are removed ample space is afforded for the tools necessary to operate the mandrels, inserted through the plug holes, to connect or disconnect the superheater elements or tubes from the bottom of the header, and also for removing scale or other mineral deposit from the various compartments. The compartments for steam and the longitudinal passages for saturated steam are formed by transverse partitions 100 cast integral with the main portion of the header. These partitions 100 also form the hot-air pockets 101 which are constantly open to the smoke box on their front and lower sides, so that the products

of combustion have free access to the longitudinal connecting tubes 10. The large openings of the compartments at the front side of the header also enable the headers to be formed of cast metal and to be very sound and free from cold-shots and blow-holes.

With the superheater in action saturated steam enters the central saturated steam compartment 7 of the header through the passage 18^b in the header, and also enters the saturated steam compartments 7^a and 7^b through the connecting channels or passages 9 in the header. The saturated steam then passes through each of the superheater 80 pipe ends 5^a into and circulates through the horizontal portions of each superheater element or pipe 5, the highly superheated steam leaving the said elements and passing into the superheated steam compartments 8, 8^a and 8^b, 8^c of the header through the superheated steam outlet ends 5^b of the superheater pipes or elements, the superheated steam passing out of the header through the end compartments 8, 8^c into 90 the main steam pipes to the valve chests of the engine.

Owing to the provision of the hereinbefore mentioned short cross tubes or pipes 10, 10^a any reduction in temperature of the 95 superheated steam in the superheated steam compartments of the header,—due to the walls of said compartments being contiguous to or forming also the walls of the saturated steam compartments,—is compensated or 100 more than compensated by the hot gases issuing from the smoke or fire tubes of the boiler acting upon the said small cross pipes, thus rendering the superheater highly efficient.

The design of the header with the cross tubes 10, 10^a is such that the depth or height of the header can be increased with a possible or desired increase in the size of the smoke box, and consequently an increased 110 number of the cross tubes 10, 10^a can be employed giving a considerably increased area for the hot gases to act upon thus obtaining and maintaining a high degree of superheating of the steam.

The highly efficient steam tight joints made by expanding the ends of the superheater pipes into the bottom or tube plate of the header reduces to a minimum the amount of attention and repair necessary 120 for maintaining steam tight joints, and the consequent absence of leakage at these joints also renders the superheater highly efficient.

The provision of the removable cover 14 on the header provides for easy access to the steam compartments of the header, and not only enables the interior of the header to be readily inspected, but also enables the superheater pipe ends to be easily and quickly secured in the header, in an efficient 130

steam tight manner, and also enables the said pipes to be easily and quickly withdrawn from the header whenever it becomes necessary to do so.

5 By disconnecting the steam pipe flanges 15 and steam pipes 16 from the header, access is obtained to the end superheated steam compartments 8 and 8^a.

10 The usual damper box with damper 10 (which may be of the louver plate or other suitable kind) may be mounted in the smoke box, in the usual or any convenient manner, so as to inclose the bent ends 5^a, 5^b of the superheater elements or pipes 5, and 15 such damper may be arranged to be operated in the usual or in any suitable manner. The hereinbefore mentioned holes in the top of the header may also serve for securing to the top of and inside the header a suitable block or abutment piece for the tool, employed for forcing out the superheater pipe ends, to act against, and such block can be held in position by a bolt or the like adapted to pass through the afore- 20 said holes and can be secured by a nut on the outside of the header.

If desired instead of expanding the ends 30 of the superheater elements or pipes in the bottom of the header, they might, if desired, be secured in a steam tight manner in the bottom 6^a of the header by means of suitable nuts screwed on to the tubes both externally and internally of the header, but the preferred method of securing these pipe 35 ends is by expanding them in the header as hereinbefore described.

What I claim as my invention and desire to secure by Letters Patent is:—

1. In a superheater, the combination, with 40 superheater elements, of a header provided with integrally-formed transverse partitions which divide it into a series of compartments and longitudinal passages connecting certain of the alternate compartments 45 and extending across the intervening compartments, said series comprising a plurality of compartments for saturated steam and a plurality of compartments for superheated steam, said compartments being arranged side by side and alternately and having the said superheater elements connected to their lower parts, each steam compartment having a large opening in its front side to afford free access to its interior, and 50 removable covering means for closing the large openings so that the compartments are normally steam-tight.

2. In a superheater, the combination, with 60 superheater elements, of a header provided with integrally-formed transverse partitions which divide it into a series of steam compartments and hot-air pockets, said series comprising a plurality of compartments for saturated steam and a plurality of compartments for superheated steam, said steam 65

compartments being arranged side by side and alternately and having the said superheater elements connected to their lower parts, and each of the said hot-air pockets being formed between two of the compartments for superheated steam and being open at its front and lower sides, each steam compartment having a large opening in its front side to afford free access to its interior, removable covering means for closing the large openings of the steam compartments so that they are normally steam-tight, and steam connecting pipes extending across the said hot-air pockets between the adjacent chambers for superheated steam.

3. In a superheater, the combination, with 70 superheater elements, of a header provided with integrally-formed transverse partitions which divide it into a series of steam compartments, hot-air pockets, and longitudinal passages connecting certain of the alternate steam compartments and extending above and across the intervening steam compartments, said series comprising a plurality of compartments for saturated steam and a 75 plurality of compartments for superheated steam, said steam compartments being arranged side by side and alternately and having the superheater elements connected to their lower parts, and each of the said hot-air pockets being formed between two of the compartments for superheated steam and being open at its front and lower sides, each steam compartment having a large opening in its front side to afford free access to its interior, removable covering means for closing the large openings of the steam compartments so that they are normally steam-tight, and steam connecting pipes extending across the said hot-air pockets between the adjacent chambers for superheated steam.

4. A steam superheater for fire tube boilers, comprising a header provided with a

number of compartments, a portion of the 110 compartments having communication with a source of saturated steam supply, one wall of the header being removably secured in place, a series of superheater elements communicating with the compartments provided with the saturated steam and extending into the fire tubes of the boiler with their opposite ends communicating with the other compartments of the header, said last mentioned compartments having communication with 115 the steam chests of the cylinders, the compartments communicating with the saturated steam supply and those communicating with the steam chests of the cylinders being alternately arranged, means whereby 120 communication between adjacently placed superheated steam compartments is established, said means being arranged in the path of the gases of combustion.

5. A steam superheater for fire tube boil-

ers, comprising a header adapted to be arranged transversely of the boiler and having a series of compartments, one set of the compartments having communication with a 5 source of saturated steam supply while the other set has communication with the steam chests of the cylinders, the compartments of the different sets being alternately arranged, communication between the saturated steam 10 compartments being arranged within the header and to one side of the superheated steam compartments, conduits for establishing communication between the adjacently arranged superheated steam compartments, 15 said conduits being arranged in the path of the gases of combustion, and a series of tubes leading from the saturated steam compartments into the fire tubes of the boiler and communicating at their opposite ends with 20 the saturated steam compartments.

6. A steam superheater for fire tube boilers, comprising a header arranged transversely of the boiler and above the fire tubes thereof, one wall of the header being removably secured in place, a series of compartments arranged transversely in the header and forming a group of saturated steam compartments and a group of superheated steam compartments, the saturated steam 25 and superheated steam compartments being alternately arranged, with the saturated steam compartments having communication with each other at the upper part of the header, the intermediate or center compartment having communication with a source of 30 saturated steam supply while the end compartments have communication with the steam chests of the cylinders, a series of tubes leading from the bottom of the header 35 into the fire tubes of the boiler, one end of each tube communicating with a saturated steam compartment while the other end communicates with a superheated steam compartment, and one or more conduits arranged between adjacently placed superheated steam compartments and beneath the intervening saturated steam compartment.

7. A steam superheater for fire tube boilers, comprising a header provided with a 40 series of compartments transversely arranged in the header, a connection intermediate of one of said compartments and a source of saturated steam supply, passages arranged within the header intermediate of 45 the said last mentioned compartment and

the alternately arranged compartments, said compartments being arranged at a higher level in the header than the other compartments, the end compartments having communication with the steam chests of the cylinders, a series of tubes extending from the saturated steam compartments into the fire tubes of the boiler with their opposite ends communicating with the adjacent compartments, one or more conduits 60 arranged intermediate of two alternately arranged compartments and beneath the intervening saturated steam compartment and exterior to the header, openings arranged in the walls of the header coincident with the 65 axes of the tubes and conduits, and means whereby said openings are closed against the passage of steam.

8. A steam superheater for fire tube boilers, comprising a header provided with a 70 series of compartments, a portion of said series having communication with a source of saturated steam supply, while the other portion of said series is in communication with the steam chests of the cylinders, means 75 communicating with the saturated steam receiving portion of said series whereby the steam is superheated and conveyed to the second mentioned portion of said series of compartments, and means located exteriorly 80 of the header, intermediate of adjacently placed compartments of the second series, whereby the superheated steam is conveyed through the path of the gases of combustion.

9. A steam superheater for fire tube boilers, comprising a header provided with a 85 series of compartments, the compartments being arranged transversely in the header and forming a group of saturated steam compartments and a group of superheated 90 steam compartments, the compartments of the two groups being alternately arranged, and means located exteriorly of the header whereby communication between adjacently placed compartments of the superheated 95 steam group is established and the superheated steam is conveyed through the path of the gases of combustion.

In testimony whereof I affix my signature, in presence of two witnesses.

EDWARD SYDNEY LUARD.
